UNITED STATES PATENT OFFICE.

EMIL F. RITTER, OF SOMERVILLE, NEW JERSEY.

TOILET SEAT.

Application filed August 24, 1921. Serial No. 494,847.

To all whom it may concern:

Be it known that I, EMIL F. RITTER, a citizen of the United States, and a resident of Somerville, in the county of Somerset 5 and State of New Jersey, have invented a new and Improved Toilet Seat, of which the following is a full, clear, and exact description.

This invention relates to improvements 10 in toilet seats, particularly to an attachment for a seat which is primarily intended for use with chemical toilets and other forms of commodes.

An object of the invention is to provide 15 means associated with the seat for normally concealing the contents of the bowl and to provide means whereby a weight on the seat moves the concealing means to inoperative position.

20 A further object is to provide a device of this character for toilet seats, which will be simple and practical in construction, efficient in use, easy to clean, unlikely to get out of order and comparatively inexpensive to 25 manufacture.

With these and other objects in view, the invention consists in certain novel features of construction and combinations and arrangements of parts as will be more fully 30 hereinafter described and pointed out in the claims.

In the accompanying drawings:

Figure 1 is a top plan view of my improved toilet seat, showing the shutter in 35 closed position;

Figure 2 is a view in transverse section on the line 2—2 of Figure 1;

Figure 3 is a similar view on the line 3—3 of Figure 1, showing the shutter in 40 open position; and

Figure 4 is a fragmentary bottom plan view of the seat.

Referring in detail to the drawings, I have illustrated a conventional form of 45 chemical toilet which includes a bowl 1, brackets 2 projecting rearwardly from the bowl and a seat 3 hingedly connected at its rear end to the brackets. A lid 4 is hingedly connected to the seat 3, as indicated at 5.

50 Arcuate ribs or flanges 6 carried by the under face of the seat 3 guide the swinging movement of the seat and fit snugly within the sides of the bowl 1. Curved plates 7 fixed to the under face of the seat at opposite sides of the usual opening 8, extend 55 inwardly and downwardly into the bowl.

The adjacent edges of the plates 7 are parallel, as seen most clearly in Figure 1.

A pair of crank shafts 9 extending longitudinally of the seat 3 are mounted in 60 suitable brackets 10. The crank shafts 9 carry arcuate plates 11 adapted to close the opening between the plates 7 and conceal the contents of the bowl. The two plates 11 act as a shutter and swing laterally whenever 65 pressure is exerted on the seat 3. The crank shafts 9 are of course mounted in such a manner that the plates 11 swing clear of the plates 7.

The swinging movement of the plates is 70 accomplished by a pair of crank arms 12, integral with the shafts 9. A flat spring 13 having its intermediate portion secured to the under face of the forward end of the seat, as indicated at 14, is operatively connected at its ends to the crank arms 12, normally exerting sufficient pressure on these crank arms, to retain the shutter in closed position.

When a weight is deposited on the seat 3, 80 the crank arms 11 bearing against the edge of the bowl 1, will be turned against the tension of the spring 13 and the shutter consisting of the plates 11 will be swung open. When the weight is removed from the seat, the spring 13 will operate the crank arms to close the shutter and raise the seat, 85 as will be readily understood.

It will be seen that I have provided means for overcoming the principal disadvantage 90 and objection of chemical toilets, and although I have illustrated one of the preferred embodiments of my invention, it will be apparent that various slight changes and alterations might be made in the general 95 form and arrangement of the parts described without departing from the invention and hence I do not wish to limit myself to the precise details set forth, but shall consider myself at liberty to make such slight 100 changes and alterations as fairly fall within the spirit and scope of the appended claims.

I claim:

1. The combination with a toilet seat having an opening therein, and a bowl, of 105 crank shafts mounted on the under face of the seat, plates carried by the crank shafts cooperating to form a shutter, crank arms on the shafts, a spring acting on the crank arms 110 to normally hold the shutter in closed position, said crank arms engageable with the

bowl upon depression of the seat to open the shutter against the action of the springs.

2. The combination with a toilet seat having an opening therein and a bowl, of brackets fixed to the under face of the seat, crank shafts journaled in the brackets and extending under the opening, plates carried by the crank shafts cooperating to form a shutter, crank arms on the shafts, and means 10 acting on the crank arms to normally hold the shutter in closed position, said crank arms being engageable with the bowl upon depression of the seat to separate said plates.

15 3. The combination with a toilet seat hav-

ing an opening therein and a bowl, of brackets fixed to the under face of the seat, crank shafts journaled in the brackets and extending under the opening, plates carried by the crank shafts cooperating to 20 form a shutter, crank arms on the shafts, means acting on the crank arms to normally hold the shutter in closed position, said crank arms being engageable with the bowl upon depression of the seat to separate 25 said plates, and said means acting on the crank arms comprising a flat spring secured at its intermediate portion to the seat.

EMIL F. RITTER.
